ELECTRIC HEATING DEVICE

Joseph Colosimo, New Westminster, British Columbia, Canada

Application April 21, 1931, Serial No. 531,709, and
in Canada April 22, 1930. Renewed May 3,
1933

1 Claim. (Cl. 219—38)

My invention relates to improvements in electric heating devices which are particularly adapted for use in electric fires and the like.

The objects of the invention are to provide means for inducing air currents to flow upwards adjacent the heated element with relatively high velocity whereby the heat is rapidly distributed about the room wherein the fire is used, and also to provide means for discharging a water vapour 10 into the air current.

The invention consists essentially of a vertical tubular body heated by a suitable electrical element capable of inducing an up-current of air therethrough, and means for adding a water vapour 15 to the air current, as will be more fully described in the following specification and shown in the accompanying drawing, in which:—

Fig. 1 is a sectional view of the invention adapted for use as an electric fire.

Fig. 2 is a detail sectional view of the heating element and the water vapour tube.

In the drawing like characters of reference indicate corresponding parts in each figure.

The numeral 1 indicates generally a portable fire housing consisting of a base plate 2 supported on suitable legs 3, a back plate 4 forwardly curved at its upper extremity to deflect the heat generated outwardly into the room in which the fire is in use, a pair of vertical end panels 5 and 30 a shallow grille or open front panel 6.

The grille 6 extends but a short distance above the base plate 2 and is fitted at the front with a downwardly projecting hood 7 and at the rear in substantial alignment with said hood with a 35 baffle plate 8. The grille 6 is preferably hinged to the base 2 as at 9 to afford access to the interior of the housing.

Removably fitted upon the base 2 is a water pan 10 having a loose cover 11 which supports a 40 plurality of tubes 12 corresponding in number to the number of elements in the fire. Each of the tubes 12 is fitted at its base with a bell 13 which is adapted to be immersed in the water of the pan. Fitted in the back of the housing is a plurality 45

of pairs of terminal clips 14 which are suitably insulated and connected by wires 15 to a plug fitting or switch "not shown" to which the service wires are adapted to be connected.

A plurality of heating elements generally indicated by the numeral 16 are provided, each of which consists of a porcelain tube 17 fitted at opposite ends with metallic clips 18 which are connected together by a suitable resistance wire 19 preferably arranged in a spiral around the tube. 60 Each of the clips 18 is provided with a metallic plug 20 which is adapted to be pressed into the terminal clips 14 to connect the resistance in the electrical circuit.

The invention functions in the following manner.

When the current is switched on, the resistance wire 19 becomes heated and heats the tube 17 which being open at both ends induces an upward flow of air therethrough due to its high temperature. The air is drawn in through the grille 6 and after being heated in the tube is discharged and deflected by the back 4 into the room. The tubes 12 are heated to a relatively high 75 temperature and on account of their high conductivity heat the water in the pan 10 inducing a water vapour to rise therefrom and pass through the tubes to mix with the heated air discharged from the tube of the heating element.

What I claim as my invention is:

An electric fire comprising a tubular refractory element supporting an electrical resistance capable of connection within a circuit, means for supporting the element, a water container below the tubular element, a metallic tube extending upwards through the tubular element and projecting into the water container whereby the tube when heated will evaporate the water and cause the vapour to flow upwards therethrough, said metallic tube being of such small diameter as to afford an annular space between it and the walls of the tubular refractory element, said annular space serving as a passage for the up-flow of air.

JOSEPH COLOSIMO.
